[57] **CLAIM**

The ornamental design for a horse shoes shaped support frame for rocking chair, substantially as shown.

DESCRIPTION

FIG. 1 is a perspective side view of a horse shoes shaped support frame for rocking chair, showing my new design;

FIG. 2 is a top view thereof, drawn to a reduced scale with respect to FIG. 1.

FIG. 3 is an elevational side view thereof, drawn to a reduced scale with respect to FIG. 1.

FIG. 4 is a rear elevational view thereof drawn to a reduced scale, with respect to FIG. 1.
